Patented Oct. 10, 1922.

UNITED STATES PATENT OFFICE.

FREDERICK W. FEIHL, OF CLEVELAND, OHIO.

CONTEST SCHEDULE OR THE LIKE.

Application filed March 30, 1922. Serial No. 548,055.

To all whom it may concern:

Be it known that I, FREDERICK W. FEIHL, a citizen of the United States, residing at Cleveland, in the county of Cuyahoga and 5 State of Ohio, have invented certain new and useful Improvements in Contest Schedules or the like, of which the following is a specification.

This invention relates to printed schedules 10 for a series of contests or engagements between teams of a group, its object being to provide a simple printed schedule so arranged as to convey to the observer at a glance a variety of information. More particularly the object of the invention is to provide a printed schedule of the character described which graphically illustrates and indicates to the observer the dates and location of specific engagements between pairs 15 of teams, the open or unoccupied dates of any team, the itinerary of all teams, special events between pairs of teams, such as double headers, the general travel of sub-groups within the main group of teams, such 20 for instance, as the general travel of eastern teams to the west or vice-versa, and other information.

Further objects of the invention are in 25 part obvious and in part will appear more in detail hereinafter.

In the drawings, the view represents a portion of a printed contest schedule embodying the invention.

The printed schedule forming the present 30 invention comprises certain printed matter applied to a card or sheet 1 of paper or other suitable material and of any suitable shape and size. In the drawings, the view illustrates approximately one-third of the full 35 length of a contest schedule embodying the invention, the view being on an exaggerated scale for better illustration. It will be understood, however, that the card is usually of relatively small size so that it can be conveniently folded along the lines of fold 2 to be carried in a vest pocket or the like. On one face of said card the surface area is divided by cross-ruling or otherwise into a series of spaces 3 of convenient size and 40 shape, such spaces being arranged by the cross-ruled lines into a series of parallel or horizontal rows 4 and transversely in a series of vertical columns 5. Each of the rows of spaces is assigned by suitable designating 45 means to one of the teams of a group of teams engaging through a playing period

in a series of contests. For example, in the drawings the card shown has applied thereto a playing schedule for the National League baseball teams for the 1922 season. Therefore, opposite each of rows 4 the card is provided with a blank space 6 to which is applied the name of one of the group of National League baseball teams. These team names may be printed upon the card in 60 black or the printing may be in some special type or with some special colored ink for each team, for a purpose which will later appear, the drawings showing the names printed in black for simplicity of illustration. 65

Opposite each of the vertical columns 5 the card is provided with suitable indicia designating the several dates of engagements during the playing period. In the particular form shown, opposite each of the columns 5 are two spaces 7, 8, the spaces 7 being provided with letters to indicate days of the week and the spaces 8 being provided with numbers to indicate days of the month. 70 In ruling the card special ruled lines are preferably provided to mark off the weekly and monthly intervals. For example, between Saturday and Sunday of each week is located a heavy ruled line 9, while double 75 ruled lines 10 indicate the ends of the months, the month names being applied in spaces 11. These special ruling lines can be in special colors if desired.

The spaces 3 are provided to receive indicia for indicating engagements between particular pairs of teams of the group. One such indicia is provided for each team, the special indicia for the different teams varying from each other. For example, said 90 indicia may consist of a number of different colors or the arrangement of various kinds of cross-hatching or marking. It being impossible to show color in the drawings, the card illustrated has been provided with a 95 series of indicia consisting of various arrangements of cross-hatching, these various indicia being indicated at 12 in spaces opposite various team names. Where the several 100 indicia are colors it is obvious without illustration that the particular indicia selected for each team can be indicated to the observer by printing the name of that team in the designated color and without any necessity of special spaces for cross-hatch- 105 ing 12, as illustrated.

Referring now to a particular space, such

as the space marked 13, this space is provided with the special indicia or marking 12 corresponding to the Philadelphia team. This indicia or marking is applied to the 5 space 13, which lies in the row assigned to the Boston team. Space 13 also lies in the vertical column assigned to Thursday, April 20th. Therefore, the appearance of the Philadelphia team marking or indicia in 10 this particular space indicates to an observer that on Thursday, April 20th, the Philadelphia team engages in a contest with Boston in Boston. Likewise, the indicia at space 14 indicates that on Monday April 24th, the 15 St. Louis team engages in a contest with Cincinnati at Cincinnati. Blank spaces, such as spaces 15, 16, indicate either that the home team of that row is either idle, as in space 15, or is on the road and engaged 20 as a visitor in a contest with some other team.

With this printed schedule card it is possible to readily determine by the character of the indicia in the row of any home team at 25 what times and with what teams it engages in contests at home. Also, by picking out and following the recurrence of indicia of any particular team it is possible to readily determine the itinerary of that team as visitors from city to city. Again it will be observed that the upper four rows of the schedule shown are assigned to a sub group of eastern teams and the lower four rows to a sub group of western teams. During 35 about the first third of the schedule shown the indicia 12 are distributed fairly equally through spaces in all of the rows. Therefore, the card indicates that during this early period some eastern teams are in the west 40 and some western teams in the east. During about the next third of the schedule shown indicia are applied substantially only to 45 spaces in the lower four rows and in the final third of the schedule shown to only the upper four rows. The schedule therefore graphically indicates first an invasion of the west by eastern teams and then the invasion of the east by western teams.

The schedule may also be provided with 50 suitable special indicia for indicating special or particular events such for example, as a double header or the occurrence of two contests between a given pair of teams on a single day. In the schedule shown in the 55 drawings this special indicia comprises a pair of short parallel horizontal lines, as indicated at 17 which are applied to any given space in addition to the indicia 12. Other special marking may be employed for 60 the same purpose.

It is, of course, obvious that the invention described may be used for a variety of purposes. For example, it may be used to indicate the schedules of baseball teams, tennis 65 contests, football games, golf, hockey and

other athletic contests, debating contests and in fact may be used wherever a series of groups or individuals meet at various places on assigned dates throughout a given period. The invention may also be used for 70 business purposes, as where a number of salesmen or other employees of a company desire information about their travels, duties and the like.

It is also obvious that the schedule may 75 be produced in many ways, such as by printing, lithographing, photography or the like and that color or character of marking are equally suitable as special indicia.

What I claim is:

1. A schedule for engagements between teams of a group, or for like purposes, comprising a card having the area thereon suitably divided into parallel rows of spaces arranged transversely in columns, each row 85 being provided with indicia assigning it to a designated team of the group, and each column being provided with indicia designating a particular time during the engaging period, some of the spaces so assigned to 90 a designated team being provided with suitable indicia corresponding to other teams of the group and thereby indicating engagements with such other teams at the several times corresponding to such space. 95

2. A schedule for engagements between teams of a group, or for like purposes, comprising a card having the area thereon suitably divided into parallel rows of spaces arranged transversely in columns, each row 100 being provided with indicia assigning it to a designated team of the group, and each column being provided with indicia designating a particular time during the engaging period, some of the space so assigned to a 105 designated team being provided with suitable indicia corresponding to other teams of the group and thereby indicating engagements with such other teams at the several times corresponding to such space, and by 110 the row in which such indicia appear also indicating location of the engagement.

3. A schedule of the class described, comprising a card having the area thereon suitably divided into transversely arranged 115 rows and columns of spaces, each row having applied thereto means indicating days during the engagement period, said card being also provided with varying indicia, one for each team, whereby the appearance of one of 120 said indicia in any space indicates by the row in which said space appears the identity of the home team and by the character of the indicia the identity of the visiting team for a given engagement and by the column 125 in which it appears the time of the engagement.

4. A schedule of the class described, comprising a card having the area thereon suitably divided into transversely arranged rows 130

and columns of spaces, each row having applied thereto means indicating days during the engagement period, said card being also provided with varying indicia, one for each 5 team, whereby the appearance of one of said indicia in any space indicates by the row in which said space appears the identity of the home team and by the character of the indicia the identity of the visiting team for

a given engagement and by the column in 10 which it appears the time of the engagement, some of the spaces so provided with indicia being also provided with special indicia indicating special events.

In testimony whereof I hereby affix my 15 signature.

FREDERICK W. FEIHL.
